FIRING DEVICE OR FUSE FOR EXPLOSIVE PROJECTILES.

1,179,105.

Specification of Letters Patent. Patented Apr. 11, 1916.

Application filed May 12, 1914. Serial No. 838,119.

To all whom it may concern:

Be it known that I, WILLARD S. ISHAM, a citizen of the United States, residing at Washington, in the District of Columbia, 5 have invented a new and useful Improvement in Firing Devices or Fuses for Explosive Projectiles, which improvement is fully set forth in the following specification.

My invention relates generally to firing 10 devices or fuses for explosive projectiles, and particularly to that class of fuses in which the fuse is designed to be placed in the point of a projectile. Certain features of the invention, however, may be used in other kinds 15 of fuses.

The principal objects of the invention are to provide a fuse that will render the projectile carrying it safe to fire from high power guns, and to provide a fuse that will 20 insure explosion of the bursting charge of a projectile at such a time with reference to the impact of the projectile with different objects or materials against which it may strike, as to give the maximum effect upon 25 the target against which the attack is directed.

My device is designed especially to be employed in the class of projectiles known as torpedo shells.

30 Among the desirable results attained by the use of my novel firing device or fuse in the torpedo shell are: (1) A shell equipped with this device will explode instantly upon making either perpendicular or glancing impacts with armor, such as the thick armor of battle ships, having sufficient thickness and resistance to break up or seriously deform the shell, explosion thus occurring prior to, rather than after, penetration; (2) the shell 35 explodes very quickly after making either glancing or direct impacts with less heavy armor or other metal resistances, although these may be incapable of breaking up the shell; for example, thin armor, smoke stacks, 40 chains, torpedo boats, etc.; (3) the shell, upon striking the water, explodes after a considerable delay, whether the shell remains in the water or ricochets.

According to the present invention a shell 50 or similar projectile is provided with a firing or fuse device containing a bursting charge of a relatively insensitive explosive, said charge being ordinarily adapted to explode only upon ignition by a flame, and thus to 55 fire the relatively very large body of explosive constituting the bursting charge of the shell itself. To this end a suitable time

or delay train leads to the bursting charge of the firing device. Means operable by impact or material retardation are provided 60 for igniting this train, said means being maintained incapable of operation prior to using the shell, but being automatically brought, when the shell is thrown from a gun, into readiness for operation; it being 65 impossible in any case for ignition of the charge to occur, however, until the shell is out of and at a substantial distance from the gun, the possibility of premature explosion being thus avoided. 70

The time train may be of any desired length. It is intended that the train as a whole shall act to transmit ignition from the impact-operable means before mentioned to the bursting charge of the firing device only 75 in cases when the shell strikes a relatively yielding medium, such as water, and when the retardation of the shell, though appreciable, is relatively slight. When the impact is sharper, however, as when the shell 80 meets with the resistance of metal or the like, suitably arranged mechanism acts to cut out or eliminate the ignition train wholly or in part, so far as its normal operation is concerned, permitting the impact operated 85 ignition means to ignite the bursting charge of the firing device directly, thus causing almost instantaneous explosion of the shell charge.

The type of operation just described occurs in the device of the present invention when the resistance encountered by the shell is more intense than that offered by water, but less than that offered by a thick mass of metal such as the armor belt of a battle 90 ship. When the shell strikes a target of this latter type it is desirable to have the shell charge explode even more promptly than it will merely by cutting out the time train in the manner above explained. The de- 100 sired result may be attained by employing in the main shell charge, or in the firing device, or in both, a quantity of a more sensitive explosive which explodes by violent shock, but only under shock of the intensity developed by impact of the shell against thick masses of metal or the like. Ordinarily where the bursting charge of the shell consists wholly or in part of such an explosive, such explosive need not be used in 110 the firing device itself.

To show how these results are attained by means of the present invention, reference is had to the accompanying drawings illus-

trating typical embodiments of the broad inventive principles here involved.

In these drawings, Figure 1 is a central longitudinal section through a fuse device

- 5 or firing device constructed in accordance with the principles of the invention, the shell on which it is mounted being fragmentarily indicated; Fig. 2 is a similar section taken at right angles to Fig. 1; Fig. 3 is a section similar to Fig. 2, but shows the plunger revolved 90° to its firing position; Fig. 4 is a detail perspective of the train cutting pin; Fig. 5 is an end view of the plunger; Fig. 6 is an end view of the train plug; Fig. 7 is a central longitudinal section of another embodiment of the invention; Fig. 8 is a similar section taken at right angles to Fig. 7; Fig. 9 is a plan of the device shown in Figs. 7 and 8; Fig. 10 is a plan, and Figs. 11 and 12 are sections, in different positions, of firing pin mechanism; and Figs. 13, 14 and 15 are corresponding views of a modified form of firing pin mechanism.

25 Referring to the drawings, Figs. 1 to 6 illustrate an embodiment of the invention wherein the firing device is provided with a relatively insensitive explosive charge and with a semi-insensitive charge, said charges being contained in separate compartments. The fuse stock has a head 1 and a hollow cylindrical portion 2 exteriorly threaded to engage corresponding threads in an opening in the point of a shell 3 into which the firing device may be screwed. Recesses 3a may be provided in the outer face of the head 1 to receive a spanner or other suitable wrench device. The inner portion of the fuse stock comprises a cylindrical casing 4 which is interiorly threaded at 5 to receive a threaded coupling sleeve 6 which also engages threads on the inner surface of cylinder 2, thus firmly securing together parts 2 and 4 of the fuse stock. Located within 45 the casing 4 is a sleeve or cylinder 7 closed at its lower end 8 and open at its upper end. The upper portion of this cup-like member is exteriorly threaded to engage the inner threads in casing 4, and can thus be screwed 50 into the latter until the upper edges of the member 7 abut the lower edges of coupling member 6. A chamber or compartment 9 is thus formed to receive a charge of a relatively insensitive explosive of which ordinary black powder may be considered typical. Explosive may be charged into chamber 9 through an opening provided with a suitable closure 9a. The lower end of the casing 4 is closed by means of a threaded 55 cap or plug 10; and the chamber 11 thus formed between the threaded cap and the bottom of member 7 is intended to contain a semi-insensitive explosive. Typical explosives of this character are gun cotton, carrying a large percentage, say 10 per cent.,

of water; explosive gelatin, containing a large percentage of camphor; or any other suitable explosive that will be exploded by a violent shock sufficient to seriously deform or break up the shell, but which will not explode by shock when the shell strikes water or other material offering an approximately the same or less resistance, and which will not of course be exploded by the lesser shock incident to firing the shell from a gun. The exact degree of insensitiveness required in the explosive contained in chamber 11 is of course variable with conditions of service, depending among other things, upon the size of shell used, the dimensions and shape of the chamber in which the explosive is contained, etc. As these conditions are well known and understood by those skilled in this art, the designing of the semi-insensitive charge to meet any given requirement is a simple matter.

70 A convenient form of mechanism for firing the charge in chamber 9 will now be described. The coupling member 6 is here shown as having a contracted portion 12 which is interiorly threaded to receive a threaded train plug 13 which has a depending cylindrical projection 14 of less diameter, this depending portion being connected to the body of the train plug by a relatively thin section or neck of metal as indicated at 15. A fuse train 16 extends from the recess 17 in the train plug downwardly through the projection 14 and opens into a transverse passage 18 extending through 80 said projection and opening at its opposite ends into the chamber 9. Arranged in a central bore or passage extending axially of the fuse stock is a pin or plunger 19, one end 20 of which projects beyond the head 90 of the fuse stock and is best covered hermetically by a thin cover 21. The lower or inner end of this plunger, which may be of somewhat less diameter, fits in the recess 17 of the train plug and is slidable therein. 100 The lower end of plunger 19 may be cut on a bevel, as shown, to provide a kind of chisel edge capable of cutting the thin section or neck of metal at 15 when the plunger 19 is in operative position for this purpose 110 and is driven inwardly with sufficient force. The pin or plunger 19 is also provided with a vent passage 22-23 opening at its lower end into recess 17 and train 16 of the train plug. Extending laterally from the plunger is an 115 angular lug or arm 24 which has its lower surface formed to suitably engage the spiral or helical upper surface of an upwardly projecting portion 25 of the train plug, such upward projection and helical surface 125 extending in this instance over approximately 90° of the annular top of the train plug as shown in Fig. 6. The arm 24 of the plunger is normally supported on this sloping or helical surface in the position shown 130

in Figs. 1 and 2. In this position the lower end of plunger 19 is held away from the neck of metal at 15, and the plunger cannot operate to cut the delay train even if the shell, in being handled, were to receive a severe blow on its point as it might, for example, in accidentally falling down an ammunition hoist.

The arm 24 fits within a notch or recess in the lower portion of a hammer member 26 which fits loosely within the coupling sleeve 16 and around the pin or plunger 19. The arm 24 thus supports the hammer member and is locked thereto against relative rotation; consequently rotation of the hammer member compels said arm and plunger 19 to revolve therewith. The lower portion of the hammer is cut away as shown in Figs. 1, 2, 3 and 5 so as to permit it to revolve approximately 90° from its normal or starting position. It has a percussion cap 27 seated in a recess at its upper end, from which extends a vent passage 28 leading to vent passage 22-23 of the pin or plunger.

Secured as by screws 29 to the upper end of the coupling sleeve 6 is a disk 30 in which is mounted a firing pin 31 at the same distance from the axis of the firing device as is percussion cap 27. The end of this firing pin projects inwardly or rearwardly, and the upper surface of hammer member 26 may be provided with a groove 32 to accommodate it. Disk 30 is also provided with holes or recesses 33 and 34 adapted to receive the end of a locking pin 35 working within a cylindrical recess provided in the hammer member 26, said pin being normally pressed forwardly by a spring 36. In the arrangement here illustrated, the holes or recesses 33 and 34 lie on a circle of the same diameter as that on which percussion cap 27 is located; and when the parts are in the position illustrated in Figs. 1 and 2 recess 33 is directly over the percussion cap 27, a vacant space being thus provided above the percussion cap and serving as an additional safe-guard against accidentally striking the cap and setting it off. The recesses 33 and 34 are arranged substantially 90° apart to correspond with the extent of the sloped or helical surface on the top of the train plug. This arrangement therefore constitutes means for receiving the locking pin and securing the hammer and fuse-cutting pin or plunger 19 in proper relation with the firing pin and with the projection 25 on the train plug.

In the chamber 9 may be arranged a loose collar 37 surrounding the depending projection 14 of the train plug. Openings 38 are provided in the collar to permit ready passage of explosive from chambers 9 into the interior of the collar, and also to permit the explosion flame to pass readily from the train, or from

the cap when the train is cut out, to the explosive contained in chamber 9. It is to be understood that the space immediately surrounding the cylinder 14, as well as the passage 18, may be and usually is also filled with ignitable explosive. This loose collar, although not absolutely essential, is advantageously provided to assist in breaking off the depending portion of the train plug when the fuse device receives a transverse shock, as for example, when the shell strikes a glancing surface or strikes sidewise after ricochet.

In the lower chamber 11 may be provided a suitable weight such as cylinder 39 to increase the shock of an oblique impact or blow due to the shell striking a heavy metal mass and thus to insure explosion of the semi-insensitive explosive placed in the chamber around the cylinder. The charge in chamber 11 is, of course, designed to be exploded also in the case where the shell strikes perpendicularly against a heavy metal mass, the requisite shock being developed by the sudden retardation of the shell. It is evident that when the charge in chamber 11 is exploded in either of the ways just mentioned, such explosion occurs independently of the fuse or firing mechanism which has been described above.

The semi-insensitive explosive may be contained in a separate compartment or case as in the present instance; or it may be contained in the same compartment with the insensitive charge; or, as before stated, the semi-insensitive charge may be carried in the body of the shell itself, instead of constituting a part of the firing device proper. A semi-insensitive explosive may constitute the whole or any part of the shell charge proper. In any case, the employment of such a charge, in combination with firing mechanism of the general type above described, constitutes an important part of my invention in its most advantageous embodiment.

The operation of the parts thus far described is sufficiently obvious from the foregoing. When the projectile starts in the gun, that is, at the instant of firing the gun, the acceleration of the shell throws the locking pin 35 backward or inward, the setback releasing the hammer member 26 from its connection with the disk 30. As the shell progresses, a rotation in a right-hand or clockwise direction (viewing the shell from the rear) is imparted to it by the gun rifling. As a result, the hammer member and the pin or plunger 19 undergo, by reason of their inertia, relative rotation to the left through 90°, the rotation being limited by the shoulder 40 on the hammer member striking against the vertical face 41 of the train plug projection 25 (Fig. 3). In order that this operation may occur with certainty, it is

advantageous to form the contacting surfaces of the arm 24 and projection 25 with a slope equal to or greater than the angle of friction of the two surfaces. By thus inclining the bearing surfaces in question, the reaction of the upper surface of train plug projection 25 against the lower surface of arm 24 has a component parallel to said surfaces and tending to move arm 24 down the slope, and thus to revolve hammer 26 positively into operative position with caps 27 and pin 31 alined. Other things being equal, the magnitude of this component force for a given setback pressure depends upon the angle of slope. The force may be just about sufficient to overcome, and thus substantially to eliminate, frictional resistance; or with steeper slopes it may be much greater. In either case this component driving force is derived from setback pressure, being independent of, though supplementing, the effect of shell spin in producing relative rotation between the hammer and the other fuse parts. The parts having arrived in the position illustrated in Fig. 3, the cap 27 is now in line with the firing pin 31, while the locking pin is in line with recess or hole 33 in the disk. In the meantime the arm 24 of plunger 19 has slid off the sloping surface of the train plug projection, and the beveled end of the plunger rests on the bottom of the recess 17 at the outer or forward end of the fuse train 16 in position to cut the train at 15 when the plunger end 20 receives a blow or impact of sufficient magnitude.

When the shell passes out of the gun and ceases to receive acceleration, the reaction of spring 36 on the locking pin 35 forces the pin forward and locks the hammer member against further rotation relative to disk 30. If now the projectile in its flight is retarded by any material resistance the hammer member 26 is thrown forward by its inertia and the percussion cap is forced against the firing pin which thereupon explodes it. The flame of this explosion travels by way of passages 28, 22 and 23 to the time train 16 and ignites the same. If the resistance encountered by the projectile be due to its striking water, the plunger 19 will not receive sufficient impact to drive it inwardly so as to break the reduced metal section 15 and thus to break off projection 14 and the lower portion of the fuse or delay train. Under the conditions assumed, therefore, this train burns for a definite period and its flame therefore reaches the explosive in chamber 9 only after a definite delay. The flame upon reaching the explosive in chamber 9 ignites the charge which thereupon explodes, bursting the casing 4 and exploding the main bursting charge in the shell. This delay occasioned by the described operation of the time fuse makes it impossible, in case the percussion cap be exploded prematurely

in the gun, for explosion of the shell to occur in the gun, since the delay normally amounts to about a second of time, and during this delay the shell will have left the gun and will be several hundred feet away. 70 In case the shell strikes water, this delay also permits the shell to bury itself in the water to such a depth before exploding that it becomes a mine and is destructive at distances which have been determined by experiment and embodied in formulas. Furthermore, the delay also permits the shell to ricochet and travel a long distance before exploding, during which time it may find a target and explode by impact as hereinafter explained. 75

If the projectile in its flight strikes squarely against a thin plate of metal or other relatively hard material against which the impact is more intense than that due to 80 striking water, the protruding end 20 of plunger 19 will receive the impact and the plunger will be driven inwardly and its beveled inner end will cut the reduced metal section 15 securing projection 14 to the train 90 plug, and the projection will thereby be broken off. In the meantime the percussion cap will have been exploded by the retardation of the shell and will send its flame through passages 27, 22 and 23 directly into 95 the explosive contained in chamber 9, and a much quicker explosion of the shell will result. The result will be the same even though the delay train may have been previously ignited as a result of the shell's impact with water. The construction described therefore provides for a delayed explosion of the projectile upon relatively moderate impact or retardation through the agency 100 of a delay action train; and it also provides 105 for producing almost instantaneous explosion of the projectile upon impact which is sharper or more intense. The mechanism capable of performing these functions is normally maintained out of operative position so that neither the delayed nor the more rapid explosion can be brought about accidentally by any blows or shocks to which the projectile is liable to be subjected prior to firing. For the sake of simplicity and 110 compactness, the said mechanism is here shown as comprising but a single percussion device which may be considered to be capable of performing two distinct functions. That is to say, it may produce delayed 115 explosion through the delay action train 16; or it may flash directly into chamber 9, when the delay train has been cut out by plunger 19, to produce explosion almost instantly. While the construction here shown has peculiar advantages, it is nevertheless to be understood as illustrating merely a particularly desirable form of apparatus within the scope of the invention, which latter contemplates in its broadest aspect any arrange- 120 125 130

ment of fuse parts which is capable of producing both delayed and quick action explosion of the shell, but in which the parts are normally out of operative position for both types of explosion and can assume operative position only after the projectile has been fired.

If the shell strikes thick armor, or material offering an equivalent resistance, with such a blow as will break up the shell or seriously deform it, the shock will be sufficient to explode the semi-insensitive charge contained in chamber 11. It is a very important and essential feature of my invention in its best embodiment, however, that the charge in chamber 11 shall also be so designed that it will not explode merely upon the shell's striking water. This feature makes possible new results in the art of fuse manufacture, the object sought and obtained being practically the opposite of that which has been the basis of other fuses heretofore proposed which have been designed to permit the shell to penetrate thick armor without exploding by the shock of impact.

In Figs. 7, 8 and 9 is illustrated another form of firing device embodying the broad principles of the present invention. This embodiment of the invention has proved satisfactory in actual practice, but I do not regard it as being so advantageous a construction as that hereinabove disclosed. Referring to Figs. 7, 8 and 9, the fuse stock in this instance comprises a head portion 50 which is integral with a hollow cylindrical portion 51 closed at its inner end by a threaded plug or cap 52 which may be provided with a groove 53 to accommodate a tool for screwing the plug into place. The outer or head portion of the stock is externally threaded to engage threads in an opening in the point of the shell into which the firing device may be screwed. The projecting outer face of the fuse stock may be provided with recesses 54 to accommodate a spanner or other wrench means. Located centrally in the fuse stock is a pin or plunger 55 having an enlarged lower portion 56 fitting closely in an axial bore in the stock head and terminating in a conical point 57. Between the upper part of the plunger and the walls of the bore is a clearance space 58 which is best filled with lead, type metal, or the like, to hermetically seal the joint between the plunger and the fuse stock. An annular flange 59 in the bore normally engages the shoulder 60 of the enlarged portion of the plunger.

The outer end 61 of the plunger projects somewhat beyond the upper end of the fuse stock. In order to protect the end of the plunger from being accidentally struck before the shell is to be used, suitable means is provided to protect the same. In the present example, such means comprises a

split collar or nut 62, each section thereof having a spur or the like 63 adapted to enter a complementary recess in the plunger. The sections of the collar or nut may be held in place by pins 64 working in suitable bores in the fuse stock and normally held in the position shown in Fig. 7 by springs 65. Shallow grooves 66 are provided on the outer periphery of the split collar to receive the slightly tapered ends of the pins 64. By this arrangement, the collar, which advantageously extends a slight distance beyond the end of plunger 55, effectively protects said end from accidental blows and locks the plunger so that it cannot be driven in by any blow or shock to which a shell is subjected in handling prior to being fired.

The cylindrical chamber 51 of the firing device contains both a charge of relatively insensitive explosive 67 and a charge of semi-insensitive explosive 68, no special means being provided in this instance to separate said charges. Mechanism for firing the insensitive charge 67 will now be described. In a general way the arrangement is similar to that described in connection with Figs. 1 to 6, but involves certain important modifications. A fuse plug 69 secured as by screw threads 70 in a recess of the plug 52, incloses a chamber 71 and is surmounted by a cylindrical extension 72 terminating in a conical point 73 normally very close to the point 57 of the plunger before described. This upper portion 72 of the fuse plug is shown integral with the chambered lower portion, being connected thereto by a relatively thin section of metal at 74, so that the projecting portion 72 may be rather readily broken off the main body of the train plug. Within the projecting portion 72 is arranged an ignition train 75 at whose lower or rear end is arranged percussion cap 76, this percussion cap being located, as shown, in the upper wall of chamber 71, and substantially in the axis thereof. At its upper end, the train opens into a transverse passage 77 leading directly to the insensitive charge 67.

Fitting loosely within the chamber 71 is a cylindrical hammer 79 provided with an eccentrically disposed bore 80 within which a plug 81 is slidably arranged. The plug 81 is provided on its lateral surface with a longitudinal groove 82 which is substantially in alignment with percussion cap 76. From the lower end of this groove a passage 83 extends transversely into the plug 81, and this passage conveniently makes substantially a right angle with groove 82. One end of a pin 84, which may conveniently be simply a headless wire nail or the like, is thrust into passage 83, the remainder of the pin normally lying on the upper surface of hammer member 79. It is apparent that if the plug 81 be forced downwardly from its

elevated position shown in Figs. 7 and 10, the pin or nail 84 will be bent exactly at right angles to present its point projecting somewhat beyond the face of hammer 79 and directly in alignment with percussion cap 76, thus forming a firing pin.

Another arrangement for forming the firing pin is illustrated in Figs. 14 and 15 where the hammer 79' instead of normally resting on the cap or plug 52 is intended to remain elevated until the firing pin is to be bent into operative position. In this modification, the hammer is provided with longitudinal groove 82' and passage 83' substantially at right angles thereto, while the firing pin 84' extends into the passage 83' and overlies the top of the cylindrical plug 81' which normally rests on the closing plug 52. The outer wall of cylindrical bore 80' may be slotted as at 85 to receive the outer end of the firing pin before it is bent over. It is evident that in this modification, if the hammer 79' be forced downwardly, the pin 84' will be bent as before and will present a pin projecting beyond the face of the hammer and in alignment with the percussion cap. The operation of this modified form of the invention as illustrated more particularly in Figs. 7 to 13, is sufficiently clear from the foregoing description. At the moment the gun is fired the acceleration undergone by the shell forces the pins 64 back into their respective recesses, thus leaving the sections of the split collar 62 free to fly apart as they tend to do by reason of the centrifugal force due to the spin of the shell. At the same time, member 81, by reason of its inertia, experiences a violent set-back and is forced entirely within the bore 80, thus bending the hitherto straight pin 84 into operative position with its point in alignment with the percussion cap. The firing device is now in condition to be operated by any material retardation or impact experienced by the shell in its flight. For example, if the shell strikes water, the retardation will immediately cause forward or outward movement of hammer 79, thus forcing the firing pin against the percussion cap and igniting train 75 which will duly ignite charge 67 after a definite period of delay depending upon the length and character of the igniting train. As before, impact of the shell with water does not produce a sufficiently intense shock to explode semi-insensitive charge 68; and under these conditions, said charge does not explode until charge 67 is exploded as described. Furthermore, the impact of the point or nose of the firing device with water will not force projecting end 61 of the plunger inwardly, this movement being resisted by the lead or other soft metal surrounding the outer portion of the plunger and entering the locking groove 86 formed therein.

If the shell strikes squarely a comparatively thin metal plate or other object or material offering resistance comparable in degrees or intensity to that offered by a thin metal plate the impact will drive the pin or plunger 55 inwardly and the conical point 57 thereof will pass on one side or the other of the corresponding point on train plug projection 72, thus forcing the projection to one side and breaking it off. This cuts out the delay fuse train and the flame from the percussion cap flashes directly into the charge 67 and explodes both charges 67 and 68. If the blow be a glancing one, the transverse shock will be sufficient to break off projection 72 without the plunger 56 being driven inwardly, so that the delay action fuse will be cut out in a similar manner. If now the shell strike either glancing or squarely a mass of relatively thick metal, the shock will be sufficient to explode the semi-insensitive charge 68 immediately, entirely independently of the operation of the fuse mechanism for firing charge 67.

While the constructions above described are particularly advantageous embodiments of the present invention, it is obvious that many changes in detail can be made without departing from the spirit of the invention. For example, the arrangement of means whereby the train plug projection is broken off by the set-back of the plunger may be considerably altered. Thus, in the construction illustrated in Fig. 7, the plunger 55-56 may be simply beveled at its lower end in a manner similar to the showing of Fig. 1, instead of being provided with a conical end 57; while the upper end of projection 72 may also simply be beveled or otherwise formed so that downward movement of the plunger will cause a lateral thrust to be exerted on the train plug projection. It is apparent, therefore, than any arrangement will be suitable so long as set-back of plunger 55-56 causes the application of force transversely to the train plug projection sufficient to break it off the train plug at the reduced section or neck. Moreover, it is entirely feasible to accomplish the shortening or elimination of the delay train by entirely different means. For example, a valve or similar means, arranged to be operated by impact of the shell, may be arranged to establish direct communication at the proper time between the percussion cap and the charge to be fired. In practice, however, the arrangement of parts shown in the drawings is found to work admirably and is considered most advantageous.

Modifications such as those above mentioned and other changes of generally similar nature may be made within the limits of the invention and are included within the scope of the appended claims.

Although I have herein disclosed specific and particularly advantageous examples of the invention in which an insensitive charge is employed, it is not to be inferred that such charge is an indispensable element of the combination in all cases. I believe it to be broadly new in the projectile art to employ, in combination with a semi-insensitive charge, a time or delay fuse, or means for exploding such charge operable by impact or retardation of insufficient intensity to explode such semi-insensitive charge by shock.

For the purposes of this invention, a semi-insensitive charge or explosive may be defined as one of such character and arrangement as to be explosive by the shock due to impact of the projectile in which it is contained against thick metal armor or the like, but not explosive by the shock due to impact against water. A relatively insensitive explosive is to be understood as one which is not explosive by shock, or at least not by any shock of the character encountered in ordinary practice, but is usually exploded by a cap, either directly or through a powder train, that is, by a flame, spark, or other application of heat.

What I claim is:

1. In a fuse for shell, the combination, with an explosive charge and a firing mechanism designed to explode a cap by retardation of the shell, of a vent and delay train arranged to transmit the flame of the cap to the explosive charge, and means operable only upon impact of the required intensity to shorten the delay train.

2. Firing mechanism for projectiles comprising the combination, with a fuse stock, and a charge contained therein, of a percussion device, a time or delay action train operable thereby for igniting said charge, and means operable by impact to shorten the effective length of said delay action train.

3. In a firing device, the combination with a delay train, of a movable member capable when in operative position of cutting out the delay train upon impact with armor to effect substantially immediate explosion of the shell charge, and means normally maintaining said member in inoperative position but arranged for actuation by motion of the shell in flight to move said member into operative position.

4. Firing mechanism for projectiles comprising the combination, with a fuse stock and a delay action train therein, of a plunger projecting beyond the end of the fuse stock and arranged when driven inwardly to cut said delay train, and means normally locking said plunger in inoperative position, said means being arranged to release the plunger when the projectile is fired.

5. Firing mechanism for non-armor-piercing projectiles comprising a charge ex-

plosive by shock due to impact of the projectile in flight against thick metal but not explosive by shock due to impact against water, in combination with a charge substantially not explosive by shock but explosive by a cap, and means for exploding the latter charge, said means being operable by impact of the projectile in flight with material offering resistance equal to or greater than that offered by water.

70

75

6. In a non-armor-piercing projectile, the combination with a charge explosive by shock due to impact of the projectile in flight against thick metal but not explosive by shock due to impact against water, of a charge substantially not explosive by shock but explosive by a cap, and means for exploding the latter charge, said means being operable by impact of the projectile in flight with material offering resistance equal to or greater than that offered by water.

80

85

7. In a non-armor-piercing projectile, the combination, with a charge explosive by shock due to impact of the projectile in flight against thick metal but not explosive by shock due to impact against water, of a charge substantially not explosive by shock but explosive by a cap, and a percussion device for exploding the first mentioned charge when the projectile strikes water or thin metal.

8. In a non-armor-piercing projectile, the combination, with a charge explosive by shock due to impact of the projectile in flight against thick metal but not explosive by shock due to impact against water, of means for exploding said charge, said means being operable by impact or retardation insufficient to explode said charge by shock.

105

9. In a non-armor-piercing projectile, the combination, with a charge explosive by shock due to impact of the projectile in flight against thick metal but not explosive by shock due to impact against water, of means for exploding said charge when the shell strikes water or thin metal, said means comprising a percussion device.

110

10. In a non-armor-piercing projectile, the combination with a charge explosive by shock due to impact of the projectile in flight against thick metal but not explosive by shock due to impact against water, of a delay action fuse device arranged to be set in action upon impact with water and to detonate said charge.

115

120

11. In a projectile, the combination, with a charge explosive by shock due to impact of the projectile in flight against thick metal but not explosive by shock due to impact against water, of a delay action fuse, and a weight arranged to contact with said charge and to augment the effect of shock due to impact of the projectile.

125

130

12. In a projectile, the combination, with a delay action train, of means operable only upon impact with solid material for automatically shortening the effective length of said train, said means being normally out of operative position but being arranged to be brought into operative position by motion of the projectile in flight prior to impact. 5
13. In a projectile, the combination, with a delay action train, of means operable only upon impact with solid material for automatically shortening the effective length of said train, said means being arranged to be brought into operative position by motion of the projectile in flight. 10
14. In a projectile, the combination, with a delay action train, arranged to be set in operation by retardation of the projectile in flight, of movable means for producing almost instantaneous explosion of the projectile, said means being normally out of operative position but being arranged to be brought into operative position by motion of the projectile in flight. 15
15. In a projectile, the combination, with a delay action train, of movable means for shortening the delay train upon impact of the projectile, said means being operable by oblique or glancing impact of the projectile. 20
16. In a fuse or firing device, the combination, with percussion mechanism, of a member carrying a delay fuse or train arranged to be ignited by said percussion mechanism, a portion of said member being adapted to be broken off readily upon oblique or transverse impact of the requisite intensity, whereby the effective length of said train may be automatically shortened. 25
17. In a fuse or firing device, the combination, with a train plug having a delay fuse or train, of a movable weight arranged to strike said train plug upon oblique impact of the requisite intensity, and thereby to break said plug and cut out the train. 30
18. Firing mechanism for projectiles comprising members normally out of alinement so as to be incapable of coacting but capable of coacting to produce ignition when brought into alinement with each other, revoluble means for bringing said members into alinement, said means being arranged to utilize as a revolving force the setback pressure due to firing, and a delay action train adapted to be ignited by said members, in combination with a plunger constrained to revolve with said revoluble means into position to be driven inwardly by sufficiently intense impact and thus to shorten said delay train. 45
19. Fuse mechanism for projectiles comprising the combination, with a fuse stock having an inclined bearing, of a rotatable hammer member supported on said bearing, and a percussion device capable of being operated when the hammer member is rotated into proper position, the angle of inclination of said bearing being at least substantially as great as the angle of friction between the contacting surfaces. 60
20. Firing mechanism for projectiles comprising the combination, with a fuse stock carrying one part of a percussion igniting device, of an inclined bearing within said fuse stock, a hammer member rotatably mounted on said bearing and carrying another part of said percussion igniting device, said parts of the percussion device being normally out of alinement but capable of being brought into alinement by rotation of said hammer member on said inclined bearing relative to said fuse stock, the angle of inclination of said bearing being at least substantially as great as the angle of friction between the contacting surfaces. 65
21. In a projectile, the combination, with a delay action train, a percussion device operable upon impact of the projectile with water to ignite said train, of means for producing almost instantaneous explosion of the projectile, said means being normally out of operative position but being arranged to be brought into operative position by motion of the projectile in flight, said means moreover being operable only by impact of the projectile with solid material. 70
22. Firing mechanism for projectiles comprising the combination, with a delay action train, movable igniting means normally in inoperative position but capable when in operative position of igniting said delay train upon impact of relatively low intensity, of movable train-shortening means normally in inoperative position but capable when in operative position of shortening said delay train upon impact of an intensity greater than that sufficing to ignite said train, both said igniting means and said train-shortening means being arranged to be moved automatically into operative position by motion of the projectile in flight. 75
- In testimony whereof I have signed this specification in the presence of two subscribing witnesses.
